UNITED STATES PATENT OFFICE

FREDERICK J. RAYFIELD, OF CHICAGO, ILLINOIS, ASSIGNOR TO CHAMPION PNEUMATIC MACHINERY COMPANY, OF CHICAGO, ILLINOIS, A CORPORATION OF ILLINOIS

HOSE REEL

Application filed April 12, 1930. Serial No. 443,677.

My invention relates to reels and covers improved features of construction, arrangement and operation which may be applied to advantage to reels in general, but which are particularly adaptable, useful and efficient in connection with reels for winding up hose through which air under pressure is to be delivered, as, for example in garages or at filling stations for inflating tires.

10 An important object of the invention is to utilize the limited compression of comparatively short spring structure for resisting the unwinding and controlling the rewinding of the hose, in order that the pull 15 on the hose by the reel may be uniform throughout the range of operation.

A further object is to utilize comparatively short compression spring structure, together with a train of reduction gearing between the spring structure, a long length of hose can be accommodated and the resistant pull of the reel on the hose made uniform with only a limited distance of compression of the spring structure.

25 Still another object of the invention is to utilize the compression spring structure for absorbing the recoil or final winding up movement of the hose and eliminating the take-up of such recoil by the abutment of 30 the hose against the reel framework.

Still another important object of the invention is to provide arrangement in which only a very small and simple adjustment in the connection between the spring structure and the reduction gearing train will determine the length of hose normally depending from the reel, so that the hose end may normally be in position to be conveniently reached when service is desired.

40 Another object is to provide simple and convenient means for accurately adjusting the spring structure for the desired hose tension.

The above enumerated features and other 45 features of my invention are incorporated in the structure disclosed on the drawings, in which drawings:

Figure 1 is an elevation of one side of the reel with part of the reel frame broken away 50 and the spring structure shown in section;

Figure 2 is an elevation of the other side of the reel structure;

Figure 3 is a front elevation of the reel structure;

Figure 4 is an enlarged section on plane 55 IV—IV on Figure 3;

Figure 5 is a section on plane V—V of Figure 1; and

Figure 6 is an enlarged section similar to Figure 5 and showing in detail the connection between the reel and the supporting framework.

The supporting frame F for the reel structure comprises a hub 10 in which one end of a shaft 11 is rigidly secured as by a set-screw 12, this shaft journalling the reel R. The reel is formed of two discs 13 and 14 of sheet metal which may be secured together by spot-welding, riveting, or by means of bolts 15, shown. The peripheral sections of these discs 60 are separated to provide the annular trough or channel 16 in which a hose 17 may be wound, the channel having a width of substantially the diameter of the hose to be received. At the center of the reel the discs are 65 cut away to leave the opening 18 around which opening a supporting casting or plate 19 is secured to the reel concentric therewith, as by means of bolts or rivets 19'. The flange or plate 19 has the hub 20 receiving the shaft 70 11, and the hollow cylindrical extension 21 on the plate supports the hub 22 which also receives the shaft 11, the hub 22 having gear teeth 23. The two hubs 20 and 22 journal the reel structure on the shaft 11 and the structure is held on the shaft and against the frame F by a washer or collar 24 secured to the outer end of the shaft. The extension 21 provides the oil chamber 25 to which the shaft 11 is exposed, and, as the reel structure 75 is turned on the shaft, the bearing surfaces 80 will be kept thoroughly lubricated. The oil reservoir may be replenished through a plugged opening 26.

The supply line 27 for the compressed air 85 connects into one end of the hollow shaft 11, the other end of the shaft being connected with a coupling structure, as best shown in Figure 6, which coupling structure comprises 90 a stem or nipple 28 threading into and se- 100

cured to the outer end of the hollow shaft and having the bore 29 communicating with the bore of the hollow shaft. The nipple extends through the rear wall of the coupling body 30 which is held in place by the annular flange 31 on the nipple. A plug or cap 32 has threaded engagement with the outer end of the body 30 to form a closure therefor, and, between the plug and the flange 31, is interposed a spring 33 which tends to hold the body 30 against the inner side of the flange 31, a sealing washer 34 being interposed to seal this joint against the escape of air during relative rotation of the coupling structure and the shaft 11. The bore of the nipple 28 has the lateral outlet port 35 into the interior of the body 30, the body being connected with the exterior by a fitting 36. This fitting is connected by a preferably metallic pipe 37 with the inner end of the hose 17 on the reel.

The reel R has a perforation 38 through which extends the inner end of the hose which is secured to the reel as by means of a clip or bracket 39. This projecting inner end of the hose is connected by the pipe 37 with the fittings 36 on coupling structure C. As the reel is rotated during winding or unwinding of the hose, the connection 37 will cause the coupling member C to rotate with the reel so that the compressed air will be delivered to the hose during rotation of the reel. In order to eliminate shearing stresses in the connection 37, it is preferably a length of flexible tubing, such as copper tubing, and is bent to extend spirally from the end of the hose to the fitting 36 so that the rotation of the reel will be transmitted longitudinally through the pipe and thus eliminate shearing stresses.

A radial leg 40 extends diagonally from the frame F and its outer end supports a guide shelf 41 on which are mounted a plurality of rollers 42 around the opening 43 in the shelf through which opening the hose is drawn, the rollers forming anti-friction guides for the hose and also assisting in keeping the hose aligned relative to the reel. A wire guide frame 44 extends upwardly from the shelf with its end transversely in front of the reel groove 16 to guide and keep the hose in the groove. The end of the hose is usually provided with a grip ball 45 and a valve or outlet nozzle 46 of well-known construction for application to the valve stems of tires.

The frame F has upwardly extending divergent legs 47 and 48 supporting at their outer ends a housing 49 extending tangentially relative to the reel R. At the opposite ends of this housing are the abutment thimbles 50 and 51 which receive a rod 52. The thimble 51 has a neck 53 receiving the end of a length of tubing 54 which extends concentric with the rod 52. Surrounding this sleeve

and the rod is the main coil spring 55 which abuts against the head of the thimble 51 at one end and at its other end receives and is aligned by the neck 56 of the thimble 50 against which it abuts. Within the tube 54 is a lighter spring 57 encircling the rod and abutting against the thimbles. Threading into the thimble 51 is a plug 58 having the abutment head 59 for engagement by the hook end 60 extending from the hub 61 of a lever structure in the form of a gear sector 62 which is fulcrumed on the shaft 63 supported at the upper end of the leg 48 of the frame F. The hooked end 64 of the rod 52 receives the hook end 60 and normally this hook end abuts against the head 59 of the plug 58.

The other end of the rod 52 is threaded to receive an abutment sleeve 65 having the polygonal head 66 for receiving a wrench. Normally the thimble 51 abuts against the end wall 67 of the spring housing, this end wall having the opening 68 through which the plug 59 and the rod 52 extend to the exterior of the housing. The sleeve 65 at the other end of the rod abuts against the thimble 50, and, when the sleeve 65 is adjusted on the rod, the two springs will be put under more or less compression between the thimbles. The sleeve 65 extends through the tubular plug 69 threaded into the opening 70 in the end wall 71 of the spring housing, this plug being adjusted in accordance with the adjustment of the sleeve 65 so as to be always engaged by the thimble 50 when the reel is in normal position. The bore of the plug 69 is of sufficient diameter to receive the head 66 of the sleeve 65.

At the juncture of the legs 47 and 48 is supported a shaft 72 on which is journalled a transmission pinion 73 and a gear 74 secured thereto. The gear 74 meshes with the teeth 23 on the hub 22 forming part of the reel supporting framework, while the pinion 73 meshes with the sector gear 62, this gearing forming a reduction train between the reel and the sector 62, and, as the hook end 60 is considerably shorter than the radius of the sector 62, the movement of the rod 52 to compress the spring will be very small as compared with the rotation of the reel R and the length of the hose unwound therefrom.

Describing the operation, the sleeve 65 is adjusted so that the two springs are normally under initial compression and this compression is exerted through the rod 52 on the hook end 60 of the sector 62 and through the transmission reduction train to the reel so that, normally, the reel will be held with the hose wound up thereon, the movement of the rod 52 inwardly being limited by the abutment of the hook end 60 against the abutment plug 59.

If it is desired to use the reel, the grip ball 45 is grasped and the hose is pulled down,

such pull causing the reel R to rotate, and this rotation being communicated through the reduction gearing and the sector 62 to the hook end 60 which swings outwardly and 5 pulls with it the rod 52. Such outward pull of the rod is communicated through the sleeve 65 to the thimble 50 and to the springs which are then compressed, such compression of the springs resisting the rotation of the reel by 10 the pull on the hose. Owing to the reduction and leverage connection between the reel and the rod 52, the compression movement of the springs will be very little as compared to the length of hose unwound from the reel and, 15 therefore, the springs will afford practically uniform resistance to pull on the hose throughout the entire range of operation of the reel, i. e., whether the hose is only partly unreeled or entirely unreeled.

20 During unreeling of the hose, the hook end 60 of the sector 62 is withdrawn from the abutment plug 69. When the hose is released, the springs will return to their normal position and the pull thereof is exerted through 25 the reduction train on the reel, and the reel is rotated to wind up the hose. The reduction train offers more or less resistance to such wind-up movement, but the rewinding movement may, nevertheless, be quite rapid, and 30 unless checked and cushioned, there might be considerable impact when the parts return to their normal positions. It will be noted, however, that, as soon as the hook end 60 on the sector 62 returns into engagement with 35 the abutment plug 59, any momentum acquired by the returning parts will be expended in the compression of the springs by the impact force exerted by the hook end 60 against the plug 59 and the thimble 51 from which the plug extends. The springs thus 40 act as shock absorbers for absorbing the impact of the returning parts. After absorption of the impact, the springs return the thimble 51 into its normal position of abutment against the end wall 67. At this point, 45 the utility of the abutment plug 69 becomes apparent, this plug being adjusted in accordance with the adjustment of the sleeve 65 so that, after the springs return to their normal 50 compression, the thimble 50 will be in abutment with the plug 69 to take up the further compression of the springs under the impact pressure when the parts return during the 55 rewinding operation.

55 By using the auxiliary spring 67, a lighter main spring 55 may be used. The compression movement of the springs is very small compared to the length of the hose unwound from the reel, and, consequently, the springs 60 can act most efficiently and will maintain a practically uniform resistance to the unwinding of the reel, whether only a part or the entire length of hose is unwound. In prior 65 structures it is necessary to provide some abutment at the hose end for engaging with

a stop in order to check the rewinding movement of the reel and hose. This, of course, puts considerable strain on the hose. With my improved arrangement, in which the springs function to absorb the impact at the end of the rewinding movement, the hose remains entirely free of any strain, and it will always be accurately rewound on the reel.

The spring housing 49 is provided with ears 75 by means of which the entire reel structure may be supported upon a suitable wall or other support. Frequently the reel structure is supported from a ceiling or some other overhead support. It is very desirable that the end of the hose be at a sufficient distance above the floor so as to be out of the way, but within easy reach when its use is desired. In other words, depending upon the height of the support, the hose end should project from the reel to within easy reaching distance from the floor. Such locating of the hose end is easily established by adjustment of the abutment plug 59. When the reel support is at such a height that a greater length of hose must be left unwound in order to bring the hose end within easy reach, the plug 59 is rotated to be shifted outwardly so that the return movement of the sector 62 is shortened. If the height of the reel is such that less unwound hose length is necessary, the plug is turned to be shifted inwardly. In other words, the plug is adjusted to determine the normal position of the sector 62, so that, after the reel has been rotated in rewinding direction, it will be stopped with the desired length of unwound hose depending therefrom. To facilitate adjusting of the plug 59, it is provided with a plurality of radial holes 76 for insertion of a suitable instrument. Adjustment of the plug 59 will in no wise interfere with the operation of the springs during unwinding and rewinding of the hose and for absorbing the shock of impact of the returning parts.

I thus provide a simple, compact and efficient reel structure in which the spring structure exerts uniform power at all times and which also acts to absorb the shock of impact of the returning parts and to relieve the hose of undue strain. With my improved arrangement, a simple adjustment will determine the length of hose normally left unwound, so that the hose end will always be within easy reach from the floor.

It is evident that the various features of my invention may be utilized in reel structures for other purposes besides supporting hose for compressed air flow. It is also evident that changes and modifications in structure, arrangement and operation may be made without departing from the scope and principles of my invention.

I claim as follows:

1. In a reel structure, the combination of a supporting frame, a reel rotatably mounted

on said frame, a spring, a connection between said spring and reel whereby longitudinal movement of said spring will be accompanied by rotational movement of said reel, said spring being normally compressed to hold said connection and reel in normal position and to resist by further compression the unwinding rotation of said reel, said spring by its expansion acting through said connection to return the reel and connection to normal position when said reel is released after an unwinding movement thereof, and means whereby said spring will act by compression to absorb the impact of the returning movement of the reel and connection to normal position.

2. In a reel structure of the class described, the combination of a supporting frame, a reel rotatably mounted on said frame, a helical spring, connecting mechanism between said spring and reel, said spring being normally compressed in one direction to hold said connecting mechanism in normal position to retain the reel in wound-up position and resisting by further compression in said direction the unwinding movement of said reel, and means whereby said connecting mechanism when being returned to normal position by the expansion of said spring will impact with and cause compression of said spring in the opposite direction whereby said spring will absorb the shock of impact.

3. In a reel structure, the combination of a supporting frame, a reel rotatable on said frame for supporting a member to be unwound therefrom and rewound thereon when the reel is rotated, a spring structure, a connection between said spring structure and said reel, the force of said spring structure acting through said connection to hold said reel normally in wound-up position and to resist unwinding rotation thereof, an abutment on said spring structure engaged by said connection when said reel is returned to normal position and means whereby said spring is distorted by such engagement to thereby absorb the shock of impact thereon, said abutment being adjustable whereby to limit the return movement of said reel and leave a desired length of said member normally unwound therefrom.

4. In a reel structure of the class described, the combination of a supporting frame, a reel rotatably mounted on said frame and supporting a member to be unwound therefrom and to be rewound thereon, a compression spring supported on said frame, a connection between said spring and said reel including a lever fulcrumed on said frame and having a short lever arm engaging with one end of said spring, a rod extending from said short lever arm and having engagement with the opposite end of said spring, whereby unwinding of said member from said reel will cause compression of said spring in one

direction and return of the reel by the spring upon release of said member will return said short lever arm into engagement with the spring and said spring will be compressed in the opposite direction to cushion the impact of said arm.

In testimony whereof I have hereunto subscribed my name at Chicago, Cook County, Illinois.

FREDERICK J. RAYFIELD.
